DESIGN FOR A COMBINED LAMP AND PIPE RACK

Frank N. Mariani, New York, N. Y.

Application February 26, 1938, Serial No. 75,436

Term of patent 7 years

To all whom it may concern:

Be it known that I, Frank N. Mariani, a citizen of the United States, residing in the city, county, and State of New York, have invented a new, original, and ornamental Design for a Combined Lamp and Pipe Rack, of which the following is a specification, reference being had to the accompanying drawing, forming a part thereof, in which:

Fig. 1 is a perspective view of a combined lamp and pipe rack showing my new design.

Fig. 2 is a front elevational view of Fig. 1 and Fig. 3 is a sectional view taken on the line 3—3 of Fig. 2.

I claim:

The ornamental design for a combined lamp and pipe rack, substantially as shown.

FRANK N. MARIANI.
